Primary Examiner—Stella M Reid*Assistant Examiner*—Mark A Goodwin(74) *Attorney, Agent, or Firm*—C. Robert Rhodes; Womble Carlyle Sandridge & Rice PLLC(57) **CLAIM**

The ornamental design for a handle, as shown and described.

DESCRIPTION

FIG. 1 is a top left perspective view of a handle showing my new design;

FIG. 2 is a top plan view thereof;

FIG. 3 is a side elevational view thereof;

FIG. 4 is an end elevational view thereof; and,

FIG. 5 is a top left perspective view, illustrating the handle in a representative position on a furniture panel thereof.

FIGS. 1-3 are shown broken away to represent indeterminate length.

The broken lines depicting additional furniture portions in FIGS. 1 and 3-5 represent environmental elements only and form no part of the claimed design. The opposite side and end not shown are identical to the side and end illustrated. The underside of the handle not shown forms no part of the claimed design.
